UNITED STATES PATENT OFFICE.

JAMES EDWARD POWERS AND WILLIAM HERBERT POWERS, OF BEDFORD CITY,
VIRGINIA.

GRAIN-BINDER.

1,088,795.

Specification of Letters Patent.

Patented Mar. 3, 1914.

Application filed October 11, 1913. Serial No. 794,570.

To all whom it may concern:

Be it known that we, JAMES E. POWERS and WILLIAM H. POWERS, citizens of the United States, residing at Bedford City, 5 in the county of Bedford and State of Virginia, have invented a new and useful Grain-Binder; and we do hereby declare the following to be a full, clear, and exact description of the invention, such as will enable others skilled in the art to which it 10 pertains to make and use the same.

This invention relates to a new and useful grain binder for binding fodder or the like.

15 One of the features of the invention is the provision of a pair of members pivoted together, one having a bar provided with notches, while the other member is provided with a bar having flanges, one of which 20 is designed to engage any one of the notches of the other bar, for temporarily holding a bundle of fodder, grain or the like while being bound.

25 Another feature of the invention is the adjustability of said bars, whereby a larger or smaller bundle of fodder, grain or the like may be temporarily held for binding.

30 The invention comprises further features and combination of parts, as hereinafter set forth, shown in the drawings and claimed.

35 In the drawings: Figure 1 is a view in perspective of the improved binder constructed in accordance with the invention. Fig. 2 is an enlarged detail view of portions of the two pivoted members showing the adjustably mounted bars thereon, showing the notches of one of the bars arranged in 40 staggered relations. Fig. 3 is a plan view of portions of the members showing the same crossed, illustrating the flanged bar engaging the notches opposite those engaged in Fig. 2. Fig. 4 is a sectional view on line 4—4 of Fig. 3.

45 Referring to the drawings, 1 and 2 designate two curved members. The member 1 has a plate 3 bolted thereto by means of the bolt 4 and nuts 5, while the member 2 has a similar plate 6 secured to the same by 50 the bolts and nuts 7 and 8. The plate 6 is bifurcated, and in the bifurcation 9 a circu-

lar portion 10 of the plate 3 is received, there being a bolt 11. This bolt 11 also pivots the plates 3 and 6 to a stand or frame 12, as shown in Fig. 1. This stand or frame 55 may, if it is so desired, be dispensed with. The members 1 and 2 as shown are curved, and upon the member 2 a bar 13 is adjustably mounted by means of the bolts 14 and the slots 15. This bar 13 is constructed with 60 laterally extending flanges 16. A bar 17 curved to fit the member 1 is adjustably secured to the member 1 by means of the bolts 18 and slots 19. This bar 17 is constructed with a series of notches 20 upon each side, 65 the notches of one series on one side are arranged in staggered relations with the notches of the opposite side. The notches of either side, may be engaged by one or the other of the flanges 16 of the bar 13. 70 By the staggered arrangement of the notches, the engagement of one or the other of the flanges with one or another of the notches is easier and more accurate, and by the adjustability of the bars and the flanges 75 and notches, larger or smaller bundles may be held while being bound. The members 1 and 2 terminate in handles 21 and 22. The cord for binding the bundle has its end temporarily clamped by the clasp 23, secured 80 to one of the members 1 and 2 by the bolt 24. The cord is provided with a knot 25 to hold the cord secured against being pulled from engagement with the clasp. The cord is then wound around the bundle, one or two 85 or several times, then the knotted end of the cord is disconnected from the clasp, then the two parts of the cord are knotted together. This is accomplished while the bundle is being held by the two members. After the 90 bundle is tied the same is removed from between the members.

The invention having been set forth, what is claimed as new and useful is:

In combination, a pair of segmental 95 curved members pivoted together, the free portion of which adapted to be crossed so as to hold a bundle of grain therebetween, one of said members having a bar carried thereby provided with laterally extending 100 flanges, means for adjustably connecting said bar to its respective member whereby

the bar may be adjusted, the other member being provided with a bar having its edge portions provided with notches arranged in staggered relations, any one of the notches of either side of said bar adapted to be engaged by one of the flanges of the other bar, means for adjustably connecting the bar having the notches to its respective member whereby the bar may be adjusted.

In testimony whereof we have signed our names to this specification in the presence of two subscribing witnesses.

JAMES EDWARD POWERS.
WILLIAM HERBERT POWERS.
